[57] CLAIM

The ornamental design for a disk-drive/controller card mounting bracket, as shown and described.

DESCRIPTION

FIG. 1 is an isometric view of a disk-drive/controller card mounting bracket showing my new design; FIG. 2 is a top plan view thereof;

FIGS. 3 and 4 are respectively right and left side elevational views thereof;

FIG. 5 is a bottom plan view thereof; and

FIGS. 6 and 7 are respectively a rear view and an inverted front view thereof.

Fig.1.

Fig.2.

Fig.3.

Fig.4.

Fig.5.

Fig.6.
